UNITED STATES PATENT OFFICE.

LEO WOERNER, OF ST. LOUIS, MISSOURI.

VALVE-CONTROLLING DEVICE.

Original application filed October 19, 1922, Serial No. 595,702. Divided and this application filed December 5, 1925. Serial No. 73,463.

My invention relates to a valve controlling device such as is shown and described in my application Serial No. 595,702 filed by me October 19, 1922, of which the present application is a division.

In the accompanying drawings which illustrate one form of valve controlling device made in accordance with my invention, Figure 1 is a side elevation, the upper part being shown in section; Figure 2 is an enlarged section taken on the line 2—2 of Figure 3; Figure 3 is a side elevation taken at right angles to Figure 1; and Figure 4 is an enlarged section taken on the line 4—4 of Figure 2.

1 indicates a tubular support carried by a base 2. Secured to the support 1 at a point intermediate of its length is a bracket 3 carrying a table 4 upon which is secured the pressure controlled device not shown. The support 1 is divided into compartments by a pair of partition walls 5, spaced apart by a filler block 6. By this arrangement I provide a simple, neat and inexpensive mechanical construction in which the weight, stop member, and their attached cables (all hereinafter described) will be effectively separated so that they will not interfere with each other during the operation of the device. Arranged in the central compartment is a stop member 7 provided with an inclined face 8, which face cooperates with a corresponding face 9 carried by a detent 10. The detent 10 is pivoted to the support 1 at 11 and is retained in normal position by an antifriction roller 12. The roller 12 is carried by an arm 13 pivoted at 14 and provided with a down-turned end 15, by means of which the arm is actuated to release the stop member, as will be hereinafter described. A spring 30 returns the arm 13 to normal position. Attached to the lower end of the stop member 7 is a cable 16 which passes downwardly, around a sheave 17 and thence upwardly and around a second sheave 18. The end of the cable 16 is secured to a lever 19 for operating a throttle valve 20 in the supply pipe 25. A rod 21 carrying an actuating weight 22 is secured to the lever 19 and passes through a guide 23. The rod 21 is provided with a head 24 adapted to strike against the guide 23 and thus limit the downward movement of the weight 22. A cable 26 is attached to the upper end of the stop member 7 and extends

upwardly over a sheave 27 and thence downwardly to a weight 28 in one of the lateral compartments of the support. The purpose of this weight 28 is to return the stop member 7 to normal position.

The operation of my device is as follows: An arm 31, actuated from any suitable pressure or thermal device, for example like that shown in my prior application above referred to, operates on the down-turned end 60 15 of the arm 13 to rock said arm on its pivot 14 and thus move the roller 12 out of contact with the detent 10. This releases the stop member 7 and consequently frees the weight 22 so that it may close the valve 65 20. It will be understood that the weight 22 is of sufficient mass to overcome not only the resistance of the weight 28 but also the friction of all the movable parts. To reset the device it is only necessary to raise the 70 weight 22, so that the weight 28 may return the parts to normal position and at the same time to swing the roller 12 down so that the detent 10 may engage the stop 7.

Having fully described my invention, 80 what I claim as new and desire to secure by Letters Patent of the United States is:

1. In a device of the class described, the combination with a tubular support divided into a plurality of compartments, of a stop member in one of said compartments, a flexible member extending from said stop member and adapted to control a valve, a second flexible connection extending from said stop member, and a weight carried by said second 85 named flexible connection and situated in another compartment.

2. In a device of the class described, the combination with a support, of a stop member carried thereby, a detent cooperating 90 with said stop member, a flexible member extending from said stop member and adapted to control a valve, a second flexible member extending from said stop member and tending to move it in the opposite direction 95 to said first named flexible member, and a weight carried by said second named flexible member.

3. In a device of the class described, the combination with a tubular support divided 100 into a plurality of compartments, of a stop member in one of said compartments, a detent cooperating with said stop member, a flexible member extending from said stop member and adapted to control a valve, a 105 110

- second flexible member extending from said stop member, and a weight carried by said second named flexible member and situated in another compartment.
- 5 4. In a device of the class described, the combination with a support, of a stop member carried thereby and provided with an inclined face, a detent having an inclined face cooperating with the face on said stop member, an arm controlling said detent, a connection extending from said stop member and adapted to actuate a valve, and means for returning the stop member to normal position.
- 10 5. In a device of the class described, the combination with a tubular cylindrical support, of a pair of partitions in said support, a stop member between said partitions, a valve connected to said stop member, and 20 a weight connected to said stop member for returning it to normal position when the valve is reset.
- 15 6. In a device of the class described, the combination with a tubular cylindrical support, of a pair of partitions dividing said

support into a central and two lateral compartments, a stop member in the central compartment and adapted to control a valve, and a weight in one of the lateral compartments, said weight being connected to said 20 stop member to return it to normal position when the valve is reset.

7. In a device of the class described, the combination with a tubular cylindrical support, of a pair of partitions dividing said 25 support into a central and two lateral compartments, a stop member in the central compartment and provided with an inclined face, a detent provided with an inclined face cooperating with the face on said stop member, an arm controlling said detent, a connection extending from said stop member and adapted to control a valve, and a weight in one of the lateral compartments, said weight being connected to said stop member 40 to return it to normal position when the valve is reset.

In testimony whereof, I hereunto affix my signature, this 3rd day of December, 1925.

LEO WOERNER.
